UNITED STATES PATENT OFFICE

JOHN N. RAUBER, OF ROCHESTER, NEW YORK

FORM AND MOLD FOR RADIUS CURB SECTIONS

Application filed July 9, 1928. Serial No. 291,149.

This invention relates to forms for molding radius curb sections and the like.

In molding radius curb sections such as are used in forming the boundaries of a driveway, it has been customary to erect the form or mold at the sides of the driveway in the final position of the curb section and to cast it in place. In such an arrangement it was necessary to trowel the upper surface of the section in order to present a smooth appearance, but such a troweling operation causes the water in the mixture to rise to the surface where it became covered with a film of cement which, when dried, tended to flake. The upper surface of the section is exposed to much more severe wear than the bottom portion of the section which is concealed in use and yet the denser and stronger portion of the section is at the bottom due to the fact that in a wet mixture such as is used for curb sections, the cement tends to settle to the bottom. Furthermore, the casting of the section in the position where it is to be used requires certain weather conditions and even under the best weather conditions the sections cannot be cured to give the same degree of strength as when they are cast in a factory where temperature and moisture conditions are closely regulated. I have also discovered that if there is a seam or joint in the form which permits water to leak from the mixture, there will develop roughness and weakness in the section at that point.

In accordance with the present invention it is proposed to cast radius curb sections in a factory where exact specifications of mixture, temperature, and curing, can be followed. A further feature of the invention includes the process of molding curb sections in inverted position so that the portions of the section exposed to wear are of denser texture than the portions concealed when in use, whereby it is unnecessary to employ a reenforcing metal strip on the surface of the section exposed to the greatest amount of wear or shock. An additional feature of the invention is the construction of a knock-down form or mold for radius sections which is readily assembled and disassembled and which has no seams or joints at points corresponding to the ex-

posed surface of the section, thus preventing weakness at these points due to water leaking from the mixture.

The invention will best be understood by reference to the drawing in which Figure 1 is a perspective view of a single precast curb section. Figure 2 is a plan view of the mold of this invention containing a curb section of the type shown in Figure 1, in inverted position. Figure 3 is a sectional view taken on the line 3—3 of Figure 2 while Figure 4 is an end view of the mold. Figure 5 is a side elevation of one of the end plates of the mold and Figure 6 is a sectional view thereof taken on the line 6—6 of Figure 5.

In Figure 1 there is shown a curved curb section generally designated 10 which is used in forming a driveway from a street having a boundary curbing. The section 10 is substantially oblong in cross section having one corner cut off as shown at 11 where the section is exposed to the wear of vehicles. In former concrete curbing it has been customary to insert a reenforcing strip at the rounded corner 12 to strengthen the curbing against vehicle wear. By the present process in which the curb sections are cast in inverted position, as is best shown in Figure 3, the top portion of the section 10 and especially the molded corner 12, are composed of such dense material that the reenforcing strip becomes unnecessary. The section 10 in each of its ends has a notch 13 to receive hooks or other tools for lifting the section into place. In addition these notches are filled with mortar or cement at the time the sections are put into position and since the notch 13 in block 10 registers with a similar notch in an adjoining block, they serve to lock the sections into place when the mortar or concrete hardens.

The curb section 10 of Figure 1 is cast in a mold represented in Figures 2—6. This mold consists of an arcuate sheet metal back plate 14 mounted on a frame of wood or other suitable material, the top portion of the frame being designated 15, the end members 16, and the bottom member as 17. The bottom and front side of the mold is formed as an arcuate unit structure or front portion so that there may be no seams in the exposed

top or side of the curb section. This front portion of the mold or structure consists of an integral bottom portion 18 having an arcuate shoulder 40 extending throughout its 5 length and an inclined portion 19 having a flange 20. This portion of the mold is preferably formed of cast iron or sheet metal although any arrangement may be employed in which the inner surface of the mold will 10 form a smooth surface on the portion of the section which is exposed to view when in use. The remaining front surface of this portion of the mold includes a plate 21 preferably of sheet material which is mounted on a 15 frame of wood or other suitable reenforcing material which frame includes a top member 22, vertical end posts 23 and a bottom member 24. This frame may be fastened to the flange 20 by bolts 25. The plates or end portion of 20 the mold shown in Figures 5 and 6 are generally designated 26 and are provided with a boundary flange 27 which serves to reinforce the end plate and to give an enlarged bearing surface against the front and back 25 portions of the mold. The inner surface of the end plate 26 is provided with a projection 28 of such size and shape as to form the notch 13 at the end of the section.

The mold consisting of the back-plate 14, 30 the front portion and the end plate 26 are placed in the position shown in Figures 2 and 3 in which position they are clamped in fixed position by bolts 29. It will thus be seen that the form or mold of this invention is a knock- 35 down structure which is readily stored in a minimum amount of space and in which the inner surfaces are of smooth material, readily accessible to a workman so that adhering portions of the previous curb section may be re- 40 moved and the surface treated so that the concrete mixture does not adhere thereto. In this mold since the portions 18 and 19 are of integral structure, there are no seams or joints on the surface of the section that is exposed 45 to view when it is in use.

What I claim is:

1. In a form for radius curb sections and the like, an arcuate front portion having integral horizontal and inclined up-right parts 50 corresponding to exposed portions of the section when in use, a vertical part secured to the upper edge of said inclined part, said horizontal part being provided with an arcuate shoulder near one edge, and separate 55 arcuate back plate and end plates arranged to be held in fixed relation with respect to, and having parts in engagement with the horizontal part of said front portion to provide a container from which substantially 60 none of the ingredients of the cement mixture can escape, one edge of said arcuate back plate normally engaging said shoulder.

2. In a form for a radius curb section and the like, an arcuate front portion of cast 65 metal having integral horizontal and in-

clined parts, a flange on said inclined part, a vertical sheet metal part mounted on a reinforcing frame secured to said flange, an arcuate shoulder on said horizontal part, a back plate consisting of sheet metal mounted on a reenforcing frame, detachable end plates, and means for clamping said end plates between said front plate and said back plate with the lower edge of the back plate engaging said arcuate shoulder.

In witness whereof, I hereunto subscribe my name June, 1928.

JOHN N. RAUBER.
